UNITED STATES PATENT OFFICE.

WILLIAM STEWART, JR., OF ALAMOSA, COLORADO.

SWINGING GATE.

No. 916,801.

Specification of Letters Patent. Patented March 30, 1909.

Application filed February 20, 1908. Serial No. 416,879.

To all whom it may concern:

Be it known that I, WILLIAM STEWART, Jr., a citizen of the United States, residing at Alamosa, in the county of Conejos and State 5 of Colorado, have invented a new and useful Improvement in Swinging Gates, of which the following is a specification.

This invention relates generally to gates and more particularly to a gate which is 10 swung horizontally like a pendulum upon a horizontal pivot the object being to provide an exceedingly simple construction of gate which can be quickly and easily opened and which will remain open until returned to its 15 normal or closed position by means of a lever operated means identical in construction with the means for opening said gate.

With these objects in view, my invention consists essentially in the novel features of 20 construction and combination of parts hereinafter fully described and pointed out in the claims.

In the drawing forming a part of this specification:—Figure 1 is a front view of a 25 gate constructed in accordance with my invention. Fig. 2 is an end view of the same, and Fig. 3 is a detail perspective showing a portion of the latch operating mechanism. Fig. 4 is a front view of the gate showing it in 30 a raised position.

In constructing a gate in accordance with my invention I employ the side standards A which are arranged in pairs at the proper distances and connected at their upper ends 35 by the top beam B. The standards A are spaced a sufficient distance apart to permit the gate C to swing freely between the said standards when the gate is opened, said gate being fastened to a central depending timber 40 D which swings back and forth like a pendulum carrying the gate C to the right or left as the case may be, between the standards A. The beam D is hung upon and swings upon the trunnions E mounted in 45 suitable bearings F and attached to the upper end of the timber or beam D is an open frame or track G, in which rolls a weight disk or roller H. As the gate is swung to one side or the other, the upper end of the timber is lowered and in being so lowered, the weight H is caused to roll by gravity out toward the end of the frame or track and when it reaches its extreme outward position it will counterbalance the weight of the gate proper, and hold the same opened, it being understood

that the movable weight H is sufficiently heavy for this purpose to counterbalance the gate and attached parts.

For the purpose of swinging the gate open or shut from either direction, I employ two levers I which are pivoted at I' upon beams K supported parallel with the top beam B by means of suitable inclined brackets L which extend obliquely in reverse directions from the standards A as most clearly shown. The levers I have hand-pulls I² at their outer ends, while their inner ends have depending link-rods M connected thereto, the lower ends of said rods being connected to an eye N' formed upon the outer end of an arm N, the inner end of said arm being pivoted at N² within a recess cut in the side of the timber or beam D. This arm N works up and down in a suitable guide O held in place by bracket-rods O', said guide serving to limit the movement of the arm N.

A twisted bar P is connected at its upper end to the eye N' of the arm N while its lower end is pivotally connected to a vertically movable latch-bar Q sliding in the guide-ways Q', Q² and connected to the latch R pivoted at R' to the bottom of the gate, said latch having a nose R² which engages a keeper R³ and holds the gate locked. The latch R has a vertical slot R⁴ in which works the connection between the latch and the latch-rod, so that the latch can always ride freely over the keeper when the gate is closing, irrespective of the position of the latch-bar and parts connected therewith.

Now, in operation the person approaching the gate and desiring to pass through, pulls upon the lever and this operation immediately raises the latch and after the latch has been opened the continued pull will cause the gate to swing away from the true perpendicular as indicated by the arrows, and while the gate proper is swinging to one side the frame or track carried at the upper end of the central timber is being lowered, and when the weight reaches the lowermost limit of its travel it will counterbalance the weight of the gate proper and hold it open. After passing through the hand-lever upon the opposite side is pushed upwardly and this will start the gate backward to its perpendicular position, and when it reaches its normal or closed position, the latch will automatically engage the keeper and thereby lock the gate in its closed position.

Having thus fully described my invention, what I claim as new and desire to secure by Letters Patent is:—

1. A gate having a central suspended beam, a track connected to the upper end of said beam, and a counterbalance weight movable upon the said track, for the purpose set forth.
2. A gate having a central suspended beam provided with a track at its upper end, a counterbalancing weight movable upon said track and the lever operating means for opening and closing the gate, as set forth.
3. A gate having a central suspended beam, an inclined track carried at the upper end of said beam, a counterbalance weight movable upon said track, a latch arranged at the bottom of the gate, and lever operated

means for operating the latch and opening and closing the gate, as set forth.

4. A gate having a central suspended beam, an inclined track arranged at the upper end of said beam a counterbalance weight movable upon said track, a latch pivoted to the bottom of the gate, a latch-bar connected thereto, a twisted bar connected to the latch bar, an arm pivoted to the central beam, and working in a guide which limits its movements, the link rods connected to said arm, and the levers connected to the said link-rods, said levers being arranged and operated substantially as described.

WILLIAM STEWART, JR.
